LEVERAGE WRENCH

Charles Meunier, Great Neck, N. Y.

Application October 9, 1945, Serial No. 621,221

1 Claim. (Cl. 81--88)

1

This invention relates to wrenches of the type having gripping jaws for engaging an article therebetween and the invention has particular reference to a wrench of said character for imparting reciprocatory movement to one of the jaws toward and away from the other jaw and for locking the movable jaw when the same is disposed in adjusted position.

The invention has in view a movable jaw mounted for reciprocatory movement by means of a rotatable screw connected therewith by means of a link and a pivotally connected locking handle adapted for movement of the pivotal connection with the link to a past dead center position after the movable jaw has been adjusted to the desired position with reference to the fixed jaw by rotation of the screw, the movement of the locking handle effecting a further movement of the movable jaw towards the fixed jaw for securely engaging an article between the jaws and a locking of the jaws therewith.

The invention has for a further object the provision of a holder having opposite side walls between which are mounted the movable jaw and the operating mechanism for imparting reciprocatory movement thereof toward and away from the opposite jaw affixed to the end of the holder.

The invention further comprehends a wrench of the indicated character in which the end of the holder and the locking handle adapted to be grasped for manipulating the wrench are angularly offset with reference to the gripping jaws of the wrench for facilitating manipulation of the wrench and locking handle.

With the foregoing and other objects in view reference is now made to the following specification and accompanying drawings in which is illustrated the preferred embodiment of the invention.

In the drawings:

Fig. 1 is a side view of a wrench constructed in accordance with the invention and illustrating the locking handle swung to fully open position.

Fig. 2 is a similar view illustrating the jaws in clamping engagement and in dotted outline the locking handle swung to locking position.

Fig. 3 is a top plan view of the wrench.

Fig. 4 is an enlarged vertical sectional view taken approximately on line 4--4 of Fig. 1.

Fig. 5 is a similar view taken approximately on line 5--5 of Fig. 2.

Fig. 6 is a similar view taken approximately on line 6--6 of Fig. 2.

Referring to the drawings by characters of reference, the wrench includes a holder 10 of U-

2

shaped formation in cross-sectional configuration providing opposite longitudinal extending side walls 11 and 12 which are extended outwardly at one end thereof and have secured thereto a fixed head or jaw 13 formed with a serrated gripping face 14. A movable head or jaw 15 formed with a serrated gripping face 16 is disposed in confronting relation with the fixed head or jaw 13 and is provided with a reduced longitudinal portion 17 projecting into the holder between the side walls 11 and 12 thereof for guided reciprocatory movement on transverse pins 18 projecting through a longitudinally extending slot 19 in the reduced portion 17 thereof and with their protruding ends anchored in aligned openings in the side walls 11 and 12.

In order to provide means for imparting longitudinal reciprocatory movement of the movable head or jaw 15 toward and away from the fixed head or jaw 13, a link 20 is provided which is pivoted at one end on a pivot pin 21 to the downwardly projecting bifurcated rear end of the reduced portion 17 of the movable head or jaw 15 and at the opposite end the said link is pivoted on a pivot pin 22 to the bifurcated forward end of a locking lever or handle 23. The locking lever or handle 23 is also pivoted on a pivot pin 24 to the upwardly projecting lug at the forward end of a reciprocatory bar 25 slidably arranged on the eight connecting the opposite side walls 11 and 12 of the holder and having a rearwardly extending screw 26 engaged by a thumb nut 27 with opposite peripheral portions thereof protruding through cruciform openings 28 in the opposite side walls 11 and 12 of the holder.

The bar 25 is provided with an upwardly extending projection 29 defining a stop adapted to be engaged by the locking lever 23 for limiting the inward movement thereof while a tubular roller 30 mounted on a pin 31 is adapted to engage the upper edge of the bar 25 for preventing upward tilting thereof. A longitudinally extending block 32 is secured between the opposite side walls 11 and 12 of the holder 10 with the forward end thereof engaging beneath the rearwardly projecting reduced annular boss of the thumb nut 27 for maintaining the same centrally within the cruciform openings 28. A longitudinally extending block 33 is also provided which is secured within the holder 10 beneath the movable head or jaw 15 with which it slidably engages to prevent undue wear on the pins 18.

The locking lever or handle 23 is of inverted U-shaped formation in cross-sectional configuration and the same is swingable on the pivot pin 24

to an outwardly extending position as illustrated in Fig. 1 with the pivotal connection of the link 20 therewith on the pivot pin 22 moved inwardly to a past dead center position. From said outwardly extending relation the locking lever or handle 23 is adapted to be swung to a locking position as illustrated in Fig. 2 in which the pivotal connection of the link therewith on the pivot pin 22 is moved to a past dead center position outwardly of longitudinal alignment with the pivot pins 21 and 24. In order to adjust the jaws relative to each other into gripping relation with an article therebetween the locking lever or handle 23 is swung outwardly to dispose the link 20 in inward past dead center position after which the thumb nut 27 is turned on the threaded screw 26 to effect longitudinal movement of the movable head or jaw 15 into engagement with the article. The locking lever or handle 23 is then swung inwardly to dispose the pivotal connection of the link 20 with the said lever in outward past dead center position which movement effects a tightening of the movable head or jaw 15 against the article and securely locks the same against the article so as to hold the same between the heads or jaws until released by the outward swinging of the locking lever or handle 23.

The portion of the holder 10 rearwardly of the movable head or jaw 15 is angularly offset with reference to the forward portion thereof so as to provide a clearance for manipulating the locking lever or handle 23 and to permit the gripping of the rear end portion of the wrench for manipulating the same.

What is claimed is:

In a wrench, a holder of U shaped formation in cross-section providing longitudinally extending opposite side walls and a rounded rear wall and including an elongated handle portion and a forward portion disposed at an angle to the handle portion, fixed and movable jaws carried by said forward portion, said movable jaw having a longi-

tudinally extending slot opening through the opposite sides thereof, cross pins mounted in the opposite side walls of said holder and extending through said slot for guided reciprocatory movement of said movable jaw toward and away from said fixed jaw, a longitudinally reciprocatory bar located between the side walls of the handle portion and having a threaded shank, a link pivoted at its forward end to said movable jaw, a locking handle pivoted at its inner end in spaced apart relation to the forward end of said bar and to the rear end of said link and projecting outwardly from between the walls of the handle portion on the same side thereof as said jaws for facilitating manipulation of the locking handle by the fingers of the user and said locking handle being swingable from an angular position with reference to the handle portion of said holder to a position substantially aligned therewith for moving the movable jaw toward and away from the fixed jaw and for retaining the same in locked position against an article held between the jaws and a thumb nut swivelly mounted in openings in the side walls of said handle portion and threadedly engaging said shank for imparting increments of adjustment to the movable jaw toward and away from the fixed jaw.

CHARLES MEUNIER.
